TOWER SCALE

Glenn W. Tamm, Park Ridge, Ill., assignor to
U. S. Slicing Machine Company, Inc., La Porte,
Ind., a corporation of Indiana

Application June 28, 1950, Serial No. 10,802

Term of patent 14 years

(Cl. D52—10)

To all whom it may concern:

Be it known that I, Glenn W. Tamm, a citizen of the United States, and a resident of Park Ridge, in the county of Cook and State of Illinois, have invented a new, original, and ornamental Design for Tower Scale, of which the following is a specification, reference being had to the accompanying drawings, forming a part thereof.

Fig. 1 is an elevational view illustrating the front or operator's side of the tower scale showing the new design;

Fig. 2 is a side view of the scale shown in Fig. 1 with portions of the scale platform broken away; and

Fig. 3 is an elevational view illustrating the rear or customer's side of the new design.

The dominant features of the design reside in the portions shown in full lines.

I claim:

The ornamental design for a tower scale, as shown and described.

GLENN W. TAMMEN.
